UNITED STATES PATENT OFFICE.

WERNER ZORN, OF BERLIN, GERMANY.

DIRECTION INDICATOR.

Application filed January 8, 1927, Serial No. 159,952, and in Czechoslovakia June 23, 1926.

This invention relates to signaling apparatuses for vehicles and has for its object a construction that will not only give a visible signal but will function in an unusual manner to attract attention, thereby assuring the attention of the driver of the following vehicle.

Another object of the invention is the provision of mechanism that will throw the signal blade to an exposed position and while in this position operate the same so as to attract attention to the fact that a signal has been given and the driver is about to act accordingly.

15 A feature of my invention is the novel construction of electromechanical means so that the same can be intermittently energized and de-energized so as to intermittently subject the signal arm to a magnetic traction action to cause the arm to oscillate.

It is also an object of my invention to design the mechanism to have a predetermined time action so as to regulate the oscillation of the arm in a manner to obtain 25 the best results.

Besides the above my invention is distinguished in the novel manner in which the various parts are designed and associated so that an electric circuit may be intermittently closed and opened at time intervals necessary to accomplish the best results and in such a manner that the number of movable parts are reduced to a minimum, thereby greatly prolonging the life of the 30 device and the reduction of cost of assembling.

With these and other objects in view the invention will be better understood in the following detailed description taken in connection with the accompanying drawings, wherein

40 Figure 1 is a vertical sectional view of the casing of a direction indicator showing one form of mechanism arranged therein in side elevation and also diagrammatically showing the electrical circuits associated therewith,

45 Figure 2 is a transverse section taken on the line 2—2 of Figure 1 in the direction of the arrows as shown,

50 Figure 3 is a vertical sectional view simi-

lar to Figure 1 showing a modified construction of the mechanism and

Figure 4 is a section taken on the line 4—4 of Figure 3 in the direction of the 55 arrows as shown.

Again referring to the drawings and more particularly to the construction shown in Figure 1, the numeral 1 designates the casing having a slot 2 in the side thereof to accommodate the swinging movement of the signal arm 3. This signal arm 3 is mounted on the pivot 4 so as to swing to a horizontal exposed position as illustrated or to a vertical inexposed position 60 within the casing. Secured to the pivot 4 is a segmental counter weight 5 arranged in a predetermined position relative to the signal blade so that the weight thereof may be utilized and combined with the weight 65 of the signal blade to move the blade to a position within the casing and hold the same therein against accidental displacement. Passed around the curved surface of the counter weight is a strap 6 having one end secured to the counterweight as indicated at 7 with the other end portion 70 passed beyond the weight and secured to a coil spring 9 that in turn connects to an armature 10 illustrated in this particular 75 case as of U-shaped formation, so that the opposed poles 11 thereof may be attracted within the magnetic coils 12 that are arranged in a circuit 13 diagrammatically 80 illustrated.

85 This circuit 13 includes a switch 14 which controls the continuity of the circuit and thereby regulates the magnetic attraction of the coils for the armature. This switch 14 is under the control of the signal arm so that when the signal arm reaches its displaying position the switch will be opened for interrupting the circuit to the coils and as the coils lose their magnetic attraction it will be readily understood that the signal 90 arm will gravitate towards its vertical position. As the signal arm descends the switch will be relieved of the influence of the signal arm and will return to its closed position for again passing current to the 95 coils 12 for energizing the same. Upon energization of the coils the armature will 100

be attracted and thus the signal arm is thrown again to its horizontal position. By interposing the coil spring 9, the shock of these impulses is reduced and a more even 5 uniform action of the parts is assured.

As far as I have proceeded it will be noted that the signal arm is subject to rapid oscillatory movement and if found advisable in practice, the oscillation may be prolonged and for accomplishing this result, I have illustrated in Figures 3 and 4 another construction of switch mechanism whereby the oscillation of the switch arm may be timed to the degree found most advantageous in practice.

In this particular case the switch 16 is also in the form of a spring strip so as to have yieldable action toward and away from the stationary contact 17. The arm 18 10 carries a pin 19 traveling in an arcuate path to engage the free end of the switch 16 when the switch arm reaches its horizontal position so as to move the switch 16 out of engagement with the contact 17 and thereby 15 interrupt the circuit for allowing the signal arm to gravitate. Simultaneously with this action the switch acts upon a cam shaped extension 21 to force the catch 22 in a direction to allow the switch 16 to snap 20 behind the shoulder 23 of the extension 21 and thereby lock the switch out of engagement with this contact. This condition continues to exist until the signal arm approaches its vertical position at which time 25 the lug 24 also carried by the signal arm engages a projection or hump 25 formed on the catch in a position that the cam action between these parts will throw the catch in a direction to release the switch from the shoulder 23 so as to engage the contact 17. Immediately upon this action taking place 30 the coils are again energized for throwing the signal arm to its horizontal position to allow the same to again pass through its 35 cycle of operation. The lug 19 corresponds to the lug 15 in Figure 1 for operating the switch. Particular attention is called to the fact that the construction and arrangement of the switch blade, catch, lug and pin of that 40 type construction shown in Figures 2, 3 and 45 are such that the relative size may be changed or the relative spacing thereof regulated so that the swinging movements of the arm may be adjusted to meet any requirements. To complete the invention it may be 50 advisable to arrange an electric bulb 26 in the blade so that the blade may be visible at night. This electric bulb 26 may be supplied with current from a battery as is illustrated in Figure 1.

The apparatus is attached to any convenient part of the vehicle so as to be visible from the rear and the electric circuit 13 thereof is provided with a manually controlled switch 13'. Upon closing of the

switch 13', current will flow from the battery of the circuit 13 through the magnetic coils 12 which upon energization attract the armature 11 and exert a pull upon strap 6 for swinging the arm 3 about its pivot so as to assume a horizontal displaying position. Upon the arm reaching this horizontal position, the continuity of the electric circuit will be interrupted by the engagement brought about between the lugs 16 and the 70 switch 14. This interruption of the electric circuit and the de-energization of the coils 12 will release the armature 11 of the magnetic influence of the coils thereby allowing the arm 3 to gravitate to a vertical position 75 within the casing where it is effectively held against accidental displacement by the gravitation of the counterweight 5.

In the form of my invention illustrated in the drawings, the switch 14 closes previously to the arm 3 reaching its vertical position and thus the circuit is again closed for allowing the various parts to pass through their cycle of operation for returning the arm 3 to its horizontal position. It is of course to be understood that upon opening the switch 13' as heretofore set forth, the closing of the switch 14 will not effect the circuit thereby allowing the arm to remain 80 within the casing.

As is well known in the art, energization of the coils 12 intermittently will create a series of rapid magnetic impulses which is properly compensated for by the arrangement of the coil spring 9 which is illustrated 90 as interposed between the strap 6 and the armature 10.

As heretofore set forth the time intervals of the oscillations of the arm may be accurately regulated as clearly shown and illustrated by the construction and arrangement of parts illustrated in Figures 2, 3 and 4.

It is of course to be understood that the various parts may be constructed in various other manners and arranged in different arrangements, depending entirely upon the results to be accomplished and the reduction in cost of production and therefore, I do not desire to be limited in any manner except as set forth in the following claims.

I claim:

1. A signal comprising a casing, an arm pivoted to the casing to swing to a horizontal exposed position or a vertical position within the casing, electromechanical means for operating said arm, including a switch, connections between the switch and arm whereby said switch is opened, means for retaining said switch in open position when said arm reaches its horizontal position, and means for releasing the switch retaining means when the arm approaches vertical position.

2. A signal comprising a casing, an arm pivoted to the casing to swing to a horizon-

tal or vertical position, a segmental counter-weight secured to said arm, a strap secured to and passed around said weight, a spring secured to one end of the strap, an electric circuit, magnetic means for exerting a pull on said spring included in said electric circuit, a switch included in said electric circuit, a pin carried by said arm to open said switch when the arm reaches horizontal po-

sition, a catch for holding the switch in open 10 position and means engaging upon said arm approaching vertical position to relieve said catch from the switch to allow the latter to return to closed position.

In witness whereof I have hereunto set my 15 hand.

WERNER ZORN.
